UNITED STATES PATENT OFFICE.

LOUIS P. WHITEMAN, OF NEW YORK, N. Y.

DESIGN FOR A RECEPTACLE FOR MATCHES, &c.

SPECIFICATION forming part of Design No. 24,576, dated August 20, 1895.

Application filed May 8, 1895. Serial No. 548,605. Term of patent 7 years.

To all whom it may concern:

Be it known that I, LOUIS P. WHITEMAN, a citizen of the United States, residing at New York, county and State of New York, have 5 invented and produced a new and original Design for Receptacles for Matches, &c., of which the following is a specification, reference being had to the accompanying drawings, forming part thereof, in which—
10 Figure 1 is a perspective view of a receptacle made in accordance with my design, and Fig. 2 is a vertical section through the same.
The object of my invention is to provide a unique and attractive receptacle for matches
15 or other articles; and to this end said invention consists in a design for a receptacle, the leading feature of which, as shown, is a representation of a single human foot and ankle mounted upon a base of such shape and size

as to be less conspicuous than the foot and 20 ankle.

In the drawings, A designates the portion of the receptacle shaped like the human foot, and B the ankle, as both appear when nude. The cavity C of the receptacle is shown as 25 formed in only the ankle portion B, and a stopper or cover D is shown as closing the same. The foot is mounted upon a base E of the shape of a parallelogram.

Having described my invention, what I 30 claim is—

The design for a receptacle for matches, &c., substantially as shown.

LOUIS P. WHITEMAN.
